REINFORCEMENT APPLICATOR

John A. Roberts, Rock Island, Ill.

Application November 4, 1948, Serial No. 58,185

4 Claims. (Cl. 1-2,1)

1

This invention relates to new and useful improvements and structural refinements in applicators for reinforcements, and the principal object of the invention is to provide an applicator such as may be conveniently and effectively employed for installing reinforcements or eyelets in "binding" apertures of leaves in loose leaf notebooks, or the like.

In particular, the invention contemplates the provision of an applicator which is adapted for use with strips of reinforcing blanks, an important feature of the invention residing in the provision of means for preforming such blanks, installing them in position on the leaf, and separating them from the main body of the strip.

An additional feature of the invention lies in the provision of automatic feeding means for passing the blanks successively through the preforming, separating and installing stations.

Important advantages of the invention reside in its simplicity of construction, convenience of operation, and in its adaptability to economical manufacture.

With the above more important objects and features in view, and such other objects and features as may become apparent as this specification proceeds, the invention consists essentially of the arrangement and construction of parts as illustrated in the accompanying drawings, in which:

Figure 1 is a top plan view of the invention;

Figure 2 is a cross sectional view, taken substantially on the plane of the line 2-2 in Figure 1 and illustrating the invention in its depressed position;

Figure 3 is a cross sectional view, similar to that shown in Figure 2, but illustrating the same in its elevated position;

Figure 4 is a fragmentary under side plan view of the applicator head, emphasizing the construction of the automatic feed mechanism, this view being taken substantially on the plane of the line 4-4 in Figure 3;

Figure 5 is a cross sectional view, taken substantially on the plane of the line 5-5 in Figure 1;

Figure 6 is a fragmentary perspective view of the feed mechanism in the head, the same being partially broken away so as to reveal its construction, and;

Figure 7 is a perspective view showing the arrangement of the preforming punch and separating blade together with their support.

Like characters of reference are employed to designate like parts in the specification and throughout the several views.

2

Referring now to the accompanying drawings in detail, the invention consists of a reinforcement applicator designated generally by the reference character 10, the same being intended for use in association with circular reinforcement blanks 12 supplied in strip form which is preferably "zig-zagged" as indicated at 14 in Figures 2, 3 and 6, that is to say, the blanks 12 are secured together at the peripheries thereof by relatively narrow necks 13 (see Figure 4) whereby the blanks in the strip may be folded one upon another in "zig-zag" formation, as will be clearly apparent. It is to be also noted that inwardly convergent recesses or notches 15 exist between the blanks 12 at the sides of the necks 13, and that the center portions of the blanks are "precut" by crossing lines, as shown at 19 in Figure 4.

The applicator 10 embodies in its construction an elongated base 20 provided adjacent one end thereof with a pair of spaced, upwardly projecting supports 22, while the remaining end portion of the base is equipped with an elevated platform 24.

An elongated head designated generally by the reference character 26 is provided on the base 20, 25 this head including a top member 28 and a bottom member 30. It is to be noted that the members 28, 30 are of a substantially U-shaped cross-sectional configuration, the bottom member 30 being straddled by the top member 28 and the members

28, 30 being pivotally secured to the support 22 of the base 20 by a transversely extending pivot pin 32. By virtue of this arrangement, the head 26 as a whole is movable on the base 20 from an elevated position shown in Figure 3 to a depressed position shown in Figure 2, a suitable spring 36 being interposed between the base 20 and the bottom member 30 of the head 26 for the purpose of urging the head to its elevated position, as will be clearly apparent. Similarly, the top member 28 is movable with respect to the bottom member 30 between an elevated position shown in Figure 3 to a depressed position shown in Figure 2, a further spring 38 being interposed between the members 28, 30 whereby the top member 28 is urged to its elevated position.

The top member 28 is provided at one end thereof with a suitable pressure pad 40 whereby the members 28, 30 may be simultaneously depressed, as indicated by the arrow 42 in Figure 3.

One end portion of the bottom member 30 provides what may be referred to as a magazine 44 for the "zig-zagged" strip of reinforcement blanks 14, and it is to be noted that the "floor" of the bottom member 30 immediately adjacent the magazine 44 is provided with spaced, double walls

44, 46 which provide therebetween a passage 48 in communication with the magazine 42. It is to be noted that the zig-zagged strip 14 may be inserted in the magazine 42 through a suitable door 50 hinged as at 52 to the aforementioned wall 44, the door 50 being openable as indicated at 54 and any suitable type of a removable cover 56 being provided on the top member 28 so that access to the interior of the head 26 may be had for the purpose of opening the door 50 and installing the strip 14 in the magazine 42. It is to be noted that the door 52 and the floor of the magazine 42 are provided with inwardly projecting detents 58, 60 respectively, which detents are intended to engage and separate, so to speak, the individual blanks 12 in the strip 14, prior to the admission of the strip 14 into the passage 48 in a flat form.

The reinforcement strip 14 is propelled through the passage 48 by an automatic feed mechanism designated generally by the reference character 62, which will be hereinafter more fully described. After leaving the passage 48, the reinforcement strip 14 is subjected to three separate and distinct operations, namely, preforming, separating and installing, this work being effected at three different locations, namely, what may be referred to as the preforming station 64, the separating station 66, and the installing station 68. As will be hereinafter more fully apparent, these various stations involve the provision of equipment or facilities on the platform 24 of the base 20, and on the bottom member 30 as well as on the top member 28 of the head 26.

The preforming station will first be described, this involving the provision of a support block 10 shown in Figure 7, which is secured to the top member 28 of the head 26 by suitable screws 12 and is equipped at the under side thereof with an acorn-shaped preforming punch 14. This punch is preferably of a hexagonal cross sectional configuration and is formed integrally with a base 16 and with a screw threaded shank 18, whereby the entire preforming punch is secured to the support block 10 by a nut 20, as will be clearly understood. Upon depression of the pad 40, that is, upon depression of the applicator to a position shown in Figure 2, the preforming punch 14 is forced through aligned, hexagon shaped openings 82, 84 in the aforementioned walls 44, 46 respectively, and through a similar, registrable opening 86 provided in the platform 24 of the base 20. The openings 82, 84 and 86 actually assume the form of a "die" for the punch 14, so that when one of the reinforcement blanks 12 is in position in the preforming station 64, upon depression of the applicator, the precut center portion of the blank will be struck out and separated into several substantially triangular sectors and these sectors will be bent downwardly as indicated at 88 in Figures 2 and 5. It should, of course, be understood that the bottom wall 46 and the passage 48 terminate at the preforming station 64, so that after the sectors 88 are formed, the blank is free to travel to the separating and installing stations 66, 68 respectively. That is to say, the aforementioned opening or aperture 84 in the wall 46 is not closed, but rather, assumes the form of an open notch or recess, from which the preformed blank may be slid laterally without obstruction.

The installing station 68 will be next described, this assuming the form of an installing punch 90 which, like the preforming punch 14, is equipped with a base 92 and with a screw-

threaded shank 94, whereby the punch 90 is secured to the platform 24 by means of a nut 96.

The installing punch 90 is receivable in a hexagonal aperture 98 formed in the wall 44 of the bottom member 30 and it is to be noted that a deflector 100 is installed on the punch 90, substantially as shown. When a preformed blank is in the installing station 68 and a "loose-leaf" 102 to which the reinforcement is to be applied is located on the punch 90 as shown in Figure 3, upon depression of the head 26 the preformed reinforcement will be brought in engagement with the punch 90 and the deflector 100 will permit the sectors 88 of the reinforcement to pass through the opening in the leaf 102 after which the reinforcement sectors 88 will be bent or doubled under the leaf 102 so that the reinforcement will be firmly and securely retained in position on the leaf.

Means are provided for separating the applied reinforcements from the main body of the strip 14, this operation being effected at the separating station 66 and involving the provision of a separating blade 104 which is secured by a screw 106 to the aforementioned support block 10. Upon depression of the head 26, the blade 104 is projected through a slot 108 formed in the aforementioned wall 44, whereby the installed reinforcement is automatically separated from the strip 14 when the head 26 is depressed.

The aforementioned feed mechanism 62 consists of a pair of spaced substantially parallel wire arms 110 which are connected together adjacent one end thereof by means of a suitable holding plate 112 and are pivotally attached as at 114 to a rod 32 provided transversely in the support 22. The free end portions of the arms 110 provide what may be referred to as a pair of arcuate feeding fingers 116 which extend through pairs of aligned slots 118 formed in the walls 44, 46, substantially as shown. In this manner, the fingers 116 extend through the reinforcement passage 48, and it is to be noted that a suitable spring 120 is provided on the pivot rod 32, this spring engaging the plate 112 and urging the fingers 116 of the arms 110 through the slots 118. Suitable pads 122 are secured to the fingers 116, these pads being slidable on the upper surface of the wall 44 and thus preventing the spring 120 from urging the fingers 116 through the slots 118 to excess.

The configuration of the slots 118 is best shown in the accompanying Figures 4 and 6, wherein it will be noted that the slots terminate at one end in outwardly arcuated portions 124, while the remaining ends thereof terminate in outwardly angulated portions 126, the fingers 116 being disposed in the slot portions 124 when the head 26 is depressed as shown in Figure 2. However, inasmuch as the pivot rods 32, 34 are spaced one from the other, raising of the head 26 in the direction of the arrow 127 will cause the fingers 116 to travel inwardly and forwardly in the slots 118 as indicated at 128 in Figure 4, until the head 26 is fully elevated as shown in Figure 3, at which point the fingers 116 will spring outwardly into the slot portions 126, as indicated at 130 in Figure 4. It should be explained at this point that the arms 110 are resilient so as to normally urge the fingers 116 outwardly into the slot portions 124, 126, the travel of the fingers through the intermediate portions of the slots 118 being effected against the resiliency of the arms 110.

Matters are so arranged that when the head 26 is moved from an elevated to a depressed

position, the fingers 116 by virtue of their arcuate configuration, simply slide upwardly over the edges of the slot portions 126 and after leaving the latter are drawn rearwardly as indicated at 132 in Figure 4, until they drop into the slot portions 124 when the head 26 is fully depressed.

Referring again to the movement of the fingers 116 in the direction of the arrows 128 when the head 26 is being elevated, the fingers while moving in this direction, of course, extend through the passage 48 and are brought in engagement with the recesses 18 between two of the reinforcement blanks, and by virtue of this engagement, the fingers 116 propel the reinforcement strip through the passage 48 toward the preforming station 64, and at the same time, propel the preformed blank from the station 64 to the installing station 68 until the fingers are disengaged from the recesses 18 and are sprung laterally into the slot portions 126. On the other hand, when the head 26 is depressed, the fingers 116 simply disengage themselves from the slot portions 126 and travel as indicated at 132 into the slot portions 124, after which the fingers engage themselves with the recesses (18) between the next adjacent set of reinforcing blanks, as will be clearly apparent. As a result, when the head 26 is depressed, one of the reinforcement blanks will be preformed in the preforming station 64 while another reinforcement blank, already preformed, is installed on the sheet 102 in the station 68 and is simultaneously separated from the strip 14 by the blade 104 in the station 66, as will be clearly understood. Thereupon, when the head 26 is raised to its elevated position, the feed mechanism 62 advances the strip 14 so that the preformed blank is brought into position in the installing station 68 and another blank is brought into position for preforming in the station 64, in readiness for the next depression or actuation of the applicator.

In conclusion, it may be explained that the top member 28 is provided under the pad 40 with an inturned flange 134, while the bottom member 30 is formed with an outturned, coacting flange 136, these flanges being engageable one with the other so as to prevent the members 28, 30 from becoming separated to an excess, as will be clearly understood.

It is believed that the advantages in use of the invention will be clearly apparent from the foregoing disclosure and accordingly, further description thereof at this point is deemed unnecessary.

While in the foregoing there has been shown and described the preferred embodiment of this invention, it is to be understood that minor changes in the details of construction and arrangement of parts may be resorted to without departing from the spirit and scope of the invention as claimed.

Having described the invention, what is claimed as new is:

1. In a reinforcement applicator, the combination of a base provided with an upstanding support, a horizontal pivot pin on said support, a depressible head mounted on said pin and provided with a reinforcement feed passage, and feeding mechanism comprising a movable member positioned in said head and including a pair of spaced arms having free end portions constituting reinforcement engaging fingers, means in

said passage for guiding the movement of said fingers in and out of reinforcement engaging positions, and a second pivot pin connecting said member to said support at a point spaced from said first-mentioned pin, whereby said member is movable in said head in response to the depression of the head relative to said base.

2. In a reinforcement applicator, the combination of a base provided with an upstanding support, a horizontal pivot pin on said support, a depressible head mounted on said pin and provided with a reinforcement feed passage, and feeding mechanism comprising a movable member positioned in said head and including a pair of spaced arms having free end portions disposed in said passage and constituting reinforcement engaging fingers, means in said passage for guiding the movement of said fingers toward and away from each other to respectively engage and disengage a reinforcement strip, and a second pivot pin connecting said member to said support at a point spaced from said first mentioned pin, whereby said member is movable in said head in response to the depression of the head relative to said base.

3. In a reinforcement applicator, the combination of a base provided with an upstanding support, a depressible head mounted on said pin and including a pair of vertically spaced bottom walls defining a reinforcement feed passage therebetween, and feeding mechanism comprising a movable member positioned in said head and including a pair of spaced resilient arms having free end portions constituting a pair of reinforcement engaging fingers, said bottom walls being provided with registering pairs of slots having spaced parallel intermediate portions and laterally extending bays at the ends of said intermediate portions, said fingers being slidable in said slots and urged into said bays by the resiliency of said arms, and a second pivot pin connecting said member to said support at a point spaced from said first mentioned pin, whereby depression and subsequent raising of said head may respectively slide said fingers through said intermediate slot portions and subsequently move the fingers over the upper of said bottom walls from one end of the slots to the other.

4. In a reinforcement applicator, the combination of a base, a depressible head mounted thereon, and reinforcement applying means comprising an upwardly tapered element having a polygonal cross-sectional configuration secured to said base, and a deflector enclosing said element and consisting of a set of upwardly convergent rods each disposed at one corner of said element, said head being provided with a polygonal opening to receive said element and said deflector.
